HOISTING MECHANISM

Robert C. Lamond, Philadelphia, Pa., assignor to
 American Engineering Company, Philadelphia,
 Pa., a corporation of Pennsylvania

Application November 21, 1935, Serial No. 50,856

23 Claims. (Cl. 254—172)

This invention relates to hoisting apparatus, and more particularly to hoisting apparatus employed on board ship or on wharves, for handling boats, airplanes, and other floating objects.

In devices of the stated character, after the object to be hoisted has been brought adjacent the ship or wharf on which the hoisting apparatus is mounted, the cable is first attached thereto. Due to the action of the waves, sudden strains are imposed upon the cable, as well as the object because of the bobbing action thereof, as well as the rolling and pitching of the ship. These sudden strains often cause either snapping of the cable or serious damage to the object handled. This is especially true in connection with airplanes, since the construction thereof is not sturdy enough to withstand sudden strains.

One object of the present invention is to provide automatic means for operating the winch to pay out cable when sudden loads are imposed thereon, and to wind in cable when any slack occurs therein.

Another object is to provide a novel mechanism for controlling the operation of such automatic means.

A more specific object is to provide in apparatus of the stated character, differential gearing between the winding drum of the winch and the operating mechanism therefor, and automatically controlled electrohydraulic means for effecting actuation of the winding drum to pay out or wind in cable independently of the operating mechanism.

Other and further objects will become apparent as the description of the invention progresses.

Of the drawings:

Fig. 1 is an elevational view of the hoisting apparatus to which the present invention is applied.

Fig. 2 is a plan view of one of the winches having associated therewith my improved tensioning device, some of the parts thereof being shown in section.

Fig. 3 is a side elevational view partly in section of the automatic tensioning device showing certain of the control elements associated therewith.

Fig. 4 is a side elevational view partly in section of the mechanism for controlling the stroking of the main pump of the hoisting apparatus, and

Fig. 5 is a side elevational view partly in section of a modified type of tensioning device.

The hoisting apparatus to which the present invention is applied is generally similar to that

shown and described in United States Patent No. 2,013,690, to which reference may be had for a full disclosure thereof.

Referring to the drawings, the numeral 1 designates a crane comprising a mast 2, and a boom 3. The lower end of mast 2 is mounted in a thrust bearing 4 and extends upwardly through a supporting structure 5, machine platform 6, and an auxiliary platform 7. Platforms 6 and 7 are secured to the mast 2 by any suitable means. 10 The mast 2 is provided with a lateral thrust bearing 8 intermediate the ends thereof, which operates in a race 9, mounted at the upper end of a supporting bracket 10. The boom 3 is pivotally supported at the lower end thereof in bearing 15 brackets 11 secured to the platform 6, as shown in Fig. 1. Mounted in a suitable framework 12, secured to brackets 10, is an internal gear 13 which meshes with a pinion 14. Pinion 14 is secured to the driven shaft 15 of an operating 20 mechanism 16 for rotating platforms 6 and 7 and mast 2 in a well known manner. Operating mechanism 16 is secured to a framework 17 and machine platform 6 in any suitable manner. Operatively associated with mast 2 and boom 3 25 are three winches 18, 19 and 20 respectively. Winch 18 is mounted in a suitable framework 21 secured to and extending upwardly from platform 7, and is employed for the purpose of swinging boom 3. Winches 19 and 20 are 30 mounted respectively in frameworks 22 and 23 secured to and extending upwardly from machine platform 6.

Winch 19 in the present apparatus is employed for handling airplanes and will be hereinafter referred to as the airplane winch, while winch 20 is employed for handling boats, such as tenders, and will hereinafter be referred to as the boat winch.

A cable 24 extends upwardly from the winding drum 25 of winch 18 and is trained around differential pulleys 26 and 27, the former being rotatably mounted in a bracket 28 secured to the top of mast 2, while the latter is similarly mounted in a bracket 29 secured to boom 3, 45 and the end of the cable is secured to a bracket 30 secured to and extending laterally of mast 2. A cable 31 extending from the winding drum 32 of airplane winch 19 is trained around a sheave 33 rotatably mounted in suitable bearings provided near the upper end of boom 3 and the end thereof is provided with the usual hook 34. A cable 35 also extends from the winding drum 36 of boat winch 20 and is trained over guide rolls 37 and 38 provided in boom 3, and thence around 50

sheave 39 rotatably mounted in a bearing bracket 40 secured to boom 3 a short distance from the upper end thereof. The cable 35 is then trained around differential pulleys 41 and 42 and the 5 end thereof is secured to a block 43 mounted on pulley 41. Pulley 42 is rotatably mounted in a bracket 44, secured to boom 3, while pulley 41 is suspended therefrom by cable 35 and the lower end of block 43 mounted thereon is provided with 10 the usual hook 45. Winches 18, 19 and 20 are respectively driven by fluid motors M1, M2 and M3 through reduction gearing designated generally by numerals 46, 47 and 48. Fluid motors M1, M2 and M3 are operated by pumps P1, P2 15 and P3 through piping connections 49, 50 and 51. Pumps P1, P2 and P3 may be interconnected for simultaneous operation by suitable driving means such as an electric motor, or separate driving means may be provided for each of said pumps. 20 Pumps P1, P2 and P3, and motors M1, M2 and M3 are of the variable stroke reversible discharge type shown and described in United States Patent No. 1,077,979 to which reference may be had for a full disclosure thereof. In pumps of this character it is well known that upon adjustment of certain controls therein to one position from neutral causes the pump to discharge in one direction, and when said controls are adjusted in the opposite direction from neutral position the 25 pump will discharge in the reverse direction. In this manner the direction of rotation of the motors driven thereby may be controlled. In the present instance control levers 55 are pivotally supported on the platform 7, each having a link 30 and lever mechanism associated therewith operatively connecting the same to the controls of the pumps P1, P2 and P3. By manipulation of these control levers 55 the boom 3 may be swung up or down by the operation of winch 18, while winches 35 40 19 and 20 may be operated respectively to either wind in or pay out cable therefrom.

In the present case the boat and airplane winches have each associated therewith an automatic tensioning device designated generally by 45 the numeral 56 for maintaining the cable taut under operating conditions.

Inasmuch as the automatic tensioning device, as well as the apparatus generally associated with the winch, is similar in each case, a description 50 of the structure and operation of the mechanisms associated with the airplane winch will suffice for both. For clarity only the controls for the transmission associated with this winch are shown in Figs. 2 to 4 of the drawings.

55 Referring more particularly to Figs. 2 and 4, it is seen that an electric motor 57 is operatively connected to pump P2 by any suitable coupling means 58. The motor M2 driven by pump P2 through the piping connections 50 has provided 60 on the drive shaft thereof a pinion 59 which meshes with a gear 60 secured to a shaft 61. Shaft 61 is mounted in suitable bearings 62 and 63 and has secured thereto intermediate its ends a pinion 64 which meshes with a gear 65. Gear 65 is rotatably supported upon a shaft 66, journaled at the ends thereof in bearings 67 and 68. Shaft 66 extends through differential gearing 69 and winding drum 32. Gear 65 has secured thereto a bevel gear 70 which meshes with a series of 70 smaller bevel gears 71 rotatably journaled on pintles 72 of a spider 73 rotatably mounted on shaft 66. The outer ends of pintles 72 are secured to worm wheel 74 and in any suitable manner. Gears 71 also mesh with a bevel gear 75 secured 75 to the hub portion 76 of winding drum 32. It

therefore is seen that when ring gear 74 is held stationary, winding drum 32 will be actuated upon operation of motor M2 through the gearing 59, 60, 64, 65, 70, 71 and 75, just described.

Control lever 55 is secured to a shaft 55a suitably journaled in a bracket 55b, secured to and depending from platform 7. Secured to and depending from shaft 55a is an arm 77, at the free end of which is pivotally connected one end of a link 78, the other end of which is pivotally connected to the free end of an arm 79, secured to a shaft 80 journaled in a second bracket 81, also secured to and depending from said platform 7. A substantially horizontal arm 82 is also secured to shaft 80 and has pivotally connected to the 1 free end thereof a yoke 83, secured to a cross bar 84. The opposite ends of cross bar 84 have secured thereto the upper ends of a pair of guide rods 85, the lower ends of which being connected to the sliding block 86 of pump P2 in a well known 21 manner. A manually operable latch 87 provided on lever 55 is adapted to engage in a notch 88 provided in a latch plate 89, mounted adjacent to lever 55, when the sliding blocks 86 of pump P2 are in neutral position. Upon releasing latch 21 87 lever 55 may be swung in either direction about its pivot to so adjust the sliding blocks 86 of pump P2 as to control the direction of rotation of winding drum 32.

The automatic tensioning device associated 30 with the winch just described consists of an hydraulic transmission 90 driven by an electric motor 91. In the present instance the transmission 90 and motor 91 are enclosed within a common 35 casing. The drive shaft 92 of the hydraulic motor end of transmission 90 has keyed thereto a worm gear 93 adapted for axial movement on said shaft. A rod 94 is secured at one end to worm gear 93, the other end being slidably mounted in a guide bracket 95 secured to the 40 other side of the casing 96 housing the differential gear 69. A coil spring 97 surrounds rod 94 and extends between the right hand end of gear 93 and the upper right hand side wall 98 of casing 96. An extension 99 is provided at the 45 left end of gear 93 (Fig. 3) having a circumferential groove 100 provided therein for receiving a pair of rollers 101 mounted at the lower ends of the legs of a yoke 102. Yoke 102 is secured to the lower end of the substantially vertical arm 50 103 of a bell crank lever 104 pivotally supported on a vertically extending bracket 105 secured to the upper end of casing 96 in any suitable manner. The free end of the substantially horizontal arm 106 of bell crank 104 has pivotally supported thereon the upper end of a guide rod 107 secured to and extending upwardly from the sliding block 108 of the pump end of transmission 90. Rod 94 has secured thereto near the right hand end thereof a collar 109 adapted for 55 engagement in notches 110 provided in the upper end of a yoke 111. Yoke 111 is secured to the upper end of a rod 112 guided for vertical movement in a bearing bracket 113 secured to the right hand side of casing 96. The lower end of 60 rod 112 has pivotally connected thereto the upper end of a link 114, the lower end of which being pivoted to the outer end of an arm 115 secured to a shaft 116 journaled in a bracket 117 secured to and depending from platform 7. Shaft 116 70 has also secured thereto a second arm 118 having pivotally supported at the free end thereof one end of a link 119, the other end of which being pivotally connected to the lower end of an arm 120 secured to a shaft 121, journaled in a 75

second bracket 122, also secured to and depending from platform 7. A control lever 123 is also secured to shaft 121 and extends vertically through platform 7 adjacent a latch plate 124 having notches 125, 126 and 127 respectively, provided therein. Lever 123 has also provided thereon a manually operable latch 128 adapted to engage in said notches 125, 126 or 127. Fig. 3 shows latch 128 in engagement with notch 126, at which time the collar 109 on rod 94 bears against the left hand edge 129 of the extension 130 of yoke 111. At this time worm gear 93 can only move to the left by the action of spring 97. When lever 123 is so adjusted that latch 128 engages in notch 125, yoke 111 will have been moved downwardly so as to permit worm gear 93, as well as rod 94, to move to the right by the action of gear 74, and also to the left by the action of spring 97. Lever 123 is adjusted to this position when the hoisting cable 31 is attached to the airplane so that transmission 90 will so operate the differential gearing 69 as to wind in cable when slack occurs therein and to pay out cable when a predetermined load is imposed thereon. When lever 123 is adjusted so that latch 128 engages in notch 126, as pointed out before, worm gear 93 can not slide to the right so as to pay out cable. Accordingly, lever 123 is adjusted to this position when it is desired to hoist the craft on board ship. When lever 123 is so adjusted that latch 128 engages in notch 127, yoke 111 will be moved upwardly so that the collar 109 will engage in notches 110. When in this position worm gear 93, as well as rod 94, is held against movement in either direction. Lever 123 occupies this position when it is desired to operate the winch without the use of the tensioning device, or when cable is being paid out so as to permit attachment of the hook thereon to the airplane.

From the above description of the structure of my improved apparatus the operation thereof is thought to be clear. However, in order to correlate the various elements just described, a brief description of the operation of the apparatus as a whole will now be given.

Upon energization of electric motors 57 and 91, the cylinder bodies associated with pump P2 and the pump end of transmission 90 respectively, will be rotated. Lever 123 under these preliminary conditions is adjusted so that latch 128 engages in notch 127 of latch plate 24. Latch 87 of lever 55 will now be released and the latter swung in such a direction as to cause pump P2 to actuate motor M2, which through gearing 59, 60, 64, 65 and 69 will cause winding drum 32 to pay out cable so that the hook 34 thereon may be attached to the airplane. Lever 123 is now actuated to the left (Fig. 3) until latch 128 engages in notch 125, at which time yoke 111 will be actuated downwardly to permit worm gear 93, as well as rod 94 to move in either direction. However, when sufficient cable has been unwound from drum 32 to enable attachment of hook 34 to the airplane, lever 55 is then swung to normal position shown in Fig. 4, at which time latch 87 enters notch 88 of latch plate 89 and the pump is then restored to neutral position. Motor M2 will then remain at rest, since an hydraulic lock is provided between pump P2 and motor M2, and gears 59, 60, 64 and 65, and bevel gear 70 of the differential gear 69 will also be held against movement.

Now let us assume that slack suddenly occurs in the cable due to the action of the waves.

When this occurs spring 97 will urge worm gear 93 to the left (Fig. 3) causing ring gear 74 to rotate in a counterclockwise direction. The small bevel gears 71 will now simply roll on the larger bevel gear 70 of the differential gear 69, imparting rotary movement to bevel gear 75, causing a slight rotation of the winding drum 32. When worm gear 93 moves in this manner bell crank 104 will be rocked in a clockwise direction, causing adjustment of the sliding block 108 of the pump end of transmission 90. When this occurs the motor end of the transmission will rotate the shaft 92, as well as worm gear 93 and inasmuch as bevel gear 70 is held against movement, as previously described, winding drum 32 will be actuated by bevel gears 71 operating on bevel gear 75 in such a manner as to wind in the cable 31 to take up the slack therein.

On the other hand, when a load is imposed on cable 31, winding drum 32 will tend to rotate bevel gear 75 in the reverse direction, which movement is imparted to small bevel gears 71, which roll on bevel gear 70 and tend to rotate ring gear 74 in the reverse direction. This action causes a sliding movement of worm gear 93 to the right (Fig. 3) against the action of spring 97. When the load imposed upon the cable exceeds a predetermined value, as determined by the tension of spring 97, worm gear 93 will be moved further to the right. This movement is imparted to bell crank 104 which adjusts sliding blocks 108 in the opposite direction. By this action the operation of the motor end of transmission 90 will be reversed, and worm gear 93 will now rotate in the reverse direction, causing winding drum 32 to pay out cable. In this manner the cable 31 is maintained taut and damage thereto, as well as to the object being handled, is prevented. When it is desired to hoist the airplane on board ship, lever 123 is actuated to position shown in Fig. 3, at which time latch 128 engages in notch 126. Worm gear 93, as well as rod 94, is thus prevented from movement to the right from a neutral position so that the pump end of transmission 90 can not now be so adjusted as to cause an operation of drum 32 in the direction for paying out cable. Lever 55 is now released and so adjusted as to operate the sliding blocks 86 of pump P2 in such a manner as to cause motor M2 to operate in the reverse direction, which through the train of gearing, previously described, will rotate winding drum 32, causing the latter to wind in cable and thereby enable hoising of the airplane on board ship. When the airplane has been hoisted a sufficient distance above the water so as to clear the deck, the boom 3 is swung inboard. Lever 55 is then actuated in the reverse direction to permit winding drum 32 to pay out cable so that the airplane may be landed on the deck of the ship.

Fig. 5 shows a modified type of tensioning device which employs power means for placing the pump end of the transmission on stroke in either direction to cause the associated winch to wind in or pay out cable. As shown therein, an electric motor 91' drives the hydraulic transmission 90'. The drive shaft 92' of transmission 90' has keyed thereto a worm gear 93' adapted for axial movement which meshes with the worm wheel 74' of the differential gear. Worm gear 93' has secured thereto one end of a rod 94' which is journaled in the upper right hand wall 98' of casing 96' and in bracket 95'. Rod 94' has secured thereto a collar 109' which is adapted to engage in the notches 110' of a yoke 111', se-

- cured to the upper end of a rod 112' journaled in guide bracket 113' secured to casing 96'. A coil spring 97' encircles rod 94' and extends between worm gear 93' and the wall 98' of casing 96'. In this construction axial movement is imparted to worm gear 93' by spring 97', and gear 74' in the same manner as is done by spring 97' and gear 74' respectively, of the construction shown in Figs. 1 to 4. Yoke 111' is also similarly 10 adjusted to control the axial movement of worm gear 93'. In this construction instead of the axial movement of worm gear 93' being directly imparted to the sliding blocks 108' of the pump end of the transmission, said movement is imparted to a valve 140 which controls the operation of a pair of fluid motors 141 and 142.
- Valve 140 comprises a casing 143 having a longitudinally extending chamber 144 centrally thereof in which operates a valve member 145. Casing 143 has provided therein ports 146, 147, 148 and 149. Valve member 145 comprises a pair of interconnected valve heads 150 and 151. A valve rod 152 extends through the right hand end of casing 143 and has a laterally extending pin 153 provided at the outer end thereof which engages in a slot 154 provided in the upper end of a lever 155. Lever 155 is pivoted intermediate its ends to a bracket 156 extending upwardly from casing 96' and the lower end thereof is provided with a yoke 157 which receives the upper end of collar 109'. It therefore is seen that any axial movement imparted to gear 93' and rod 94' is imparted to valve member 145. Motors 141 and 142 comprise cylinders 158 and 159 having pistons 160 and 161 respectively operating therein. The piston rods 162 and 163 respectively of pistons 160 and 161 are secured at one end thereof to the sliding block 108' of the pump end of transmission 90'. Secured to the upper end of cylinder 158 is a second cylinder 164 having a piston 165 operating therein. The lower end of the piston rod 166 of piston 165 is adapted to engage the upper end of piston 160. Cylinder 159 has secured to the lower end thereof a second cylinder 167 having a piston 168 operating therein. The upper end of the piston rod 169 of piston 168 is adapted to engage the lower end of piston 161.
- A pipe 170 extends from port 146 of valve 140 to the upper end of cylinder 158, and a branch pipe 171 connects pipe 170 with the upper end of cylinder 164. A pipe 172 extends from port 148 of valve 140 to the lower end of cylinder 167, and a branch pipe 173 connects pipe 172 to the lower end of cylinder 159. A pipe 174 extends from port 147 of valve 140 to a small pump 175 mounted at one end of the armature shaft of motor 91'. Pump 175 receives fluid such as oil from a makeup tank 176 through a pipe 177. An adjustable relief valve 178 is connected to pipe 174 by a branch pipe 179, and a discharge pipe 180 connects the lower end of said valve with makeup tank 176. Relief valve 178 is of usual construction and comprises a normally seated valve member 181 having a valve stem 182 which extends through the central bore of a plug 183 making threaded engagement with the lower end of valve 178. A coil spring 184 encircles valve stem 182 and extends between valve member 181 and the upper end of plug 183. Thus, by adjusting plug 183 the tension of spring 184 may be varied. Fig. 5 shows the parts in normal position at which time it will be noted that ports 146 and 148 of valve 140 are slightly uncovered by valve heads 150 and 151, permitting fluid entering the central chamber 144 thereof from pump 175 to pass through said ports and enter cylinders 158, 159, 164 and 167 through the piping connections previously described. When this occurs equal pressures will be exerted at the upper and lower ends of sliding blocks 108' thereby retaining the same in neutral position.
- Now let us assume that yoke 111' has been moved downwardly so that the extension 130' thereon is moved out of engagement with collar 109', and that slack occurs in the hoisting cable. Spring 97' will now urge gear 93' to the left causing lever 155 to be actuated in a clockwise direction by collar 109', thereby shifting valve member 145 to the right. When valve member 145 is so actuated valve head 150 will prevent the passage of fluid from chamber 144 to port 148. Fluid from chamber 144 now enters cylinders 158 and 164 only through pipes 170 and 171, causing pistons 160 to actuate sliding block 108' downwardly to place the pump on stroke. The motor end of transmission 90' will now rotate worm gear 93' which through the differential gearing will actuate the winch to wind in cable, thereby taking up the slack therein. Fluid from cylinders 158 and 167 will now flow through branch pipe 173, pipe 172, port 148, and into the left hand end of chamber 144. A relief valve 186 is provided at the left hand end of valve 140. This valve is of usual construction and comprises a normally seated valve member 187 having a valve stem 188 secured thereto which extends through the central bore of an adjustable plug 189, making threaded engagement with the left hand end of the casing of said cylinder. A coil spring 190 extends between the inner end of plug 189 and valve member 187. The tension of spring 190 may be adjusted by simply rotating plug 189. When the pressure at the left hand end of chamber 144 is sufficient to overcome the tension of spring 190, the fluid from cylinders 159 and 167 will discharge through port 149, and thence flow to makeup tank 176 through valve 186 and a pipe 191.
- Now let us assume that the cable of the winch is subjected to a predetermined load. Under such conditions gear 74', as previously described, will actuate worm gear 93' to the right against the action of spring 97', causing lever 155 to swing in a counterclockwise direction, thereby shifting valve member 145 to the left. When this occurs fluid will flow from central chamber 144 through pipes 172 and 173 to cylinders 167 and 159, causing sliding blocks 108' to be actuated upwardly, thereby reversing the discharge of the pump end of transmission 90' which in turn causes a reverse operation of the motor end thereof. Worm gear 93' will now operate in the reverse direction to cause the winch to pay out cable. Fluid from cylinders 158 and 164 will now flow through pipes 170 and 171 to the right hand end of chamber 144 of valve 140, thence through a passage 192, port 149, valve 186, pipe 191, and into makeup tank 176.
- When yoke 111' is in the position shown in Fig. 5, the inner surfaces 129' of the extension 130' thereof engage the right hand side of collar 109', thereby preventing axial movement of rod 94' and worm gear 93' to the right. The device is now unable to be so operated as to cause the winch to pay out cable. When yoke 111' is moved upwardly to its third position of adjustment, collar 109' engages in notches 110' and as a result worm gear 93', as well as rod 94' are held against movement. Relief valve 178 operates to bypass fluid from pump 175 to makeup tank 176 when the

pressure in the hydraulic circuit exceeds the value required to effectively control the operation of transmission 90', thus preventing damage to the apparatus. The function of valve 186 is to prevent undue leakage of fluid from the hydraulic circuit. The tension of spring 190 in said valve is so adjusted as to require but little effort to unseat valve 187. Thus the pressure at the ends of valve member 145 will not be sufficiently great to counteract, to any material degree, the axial movement of gear 93'.

While the embodiments herein described are admirably adapted to fulfill the objects previously stated, it is to be understood that the invention is not to be limited thereto, since it may be embodied in other forms, all coming within the scope of the claims which follow.

What is claimed is:

1. In a device of the class described, the combination with a winch, including a cable winding drum, of an hydraulic transmission for actuating said drum, differential gearing disposed between said drum and transmission, a second hydraulic transmission for operating said winding drum independently of said first mentioned hydraulic transmission, means operatively connecting said second hydraulic transmission to said differential gearing, and means actuated by said last mentioned means for controlling the operation of said second hydraulic transmission.

2. In a device of the class described, the combination with a winch including a cable winding drum, of an hydraulic transmission for actuating said drum to wind in or pay out cable, differential gearing disposed between said winding drum and hydraulic transmission, means for controlling the operation of said transmission, a second hydraulic transmission for operating said winding drum, a member adapted for rotary and axial movement disposed between said hydraulic second transmission and said differential gearing, and means actuated by said member for controlling the direction of rotation of said second hydraulic transmission.

3. In a device of the class described, the combination of a winch, including a cable winding drum, power means for actuating said drum in either direction, differential gearing disposed between said drum and power means, a second power means operatively connected to said gearing for actuating said drum in either direction, automatic means for controlling the operation of said second power means, and control mechanism for said automatic means having three positions of adjustment, said mechanism when actuated to one position permits movement of said automatic means in either direction from a neutral position to control the operation of said second mentioned power means, when moved to a second position, said mechanism permits movement of said automatic means in one direction only from said neutral position, and when moved to a third position said mechanism locks said automatic means against movement in either direction.

4. In a device of the class described, the combination of a winch, including a cable winding drum, an hydraulic transmission for actuating said drum to wind in or pay out cable, differential gearing disposed between said winding drum and hydraulic transmission, means for controlling the operation of said transmission, a second hydraulic transmission operatively connected to said differential gearing, automatic means disposed between said gearing and said second men-

tioned transmission for controlling the operation of the latter, said automatic means including an axially movable member, and mechanism movable to three positions of adjustment for controlling the operation of said member, said mechanism when moved to one position of adjustment permits said member to move axially in either direction from a neutral position, when moved to a second position of adjustment said mechanism permits movement of said member in one direction only from said neutral position, and when moved to a third position of adjustment said mechanism locks said member against movement in either direction.

5. In a device of the class described, the combination of a winch, including a cable winding drum, power means for actuating said drum to wind in or pay out cable, differential gearing disposed between said winding drum and power means, a second power means operatively connected to said differential gearing, automatic means disposed between said gearing and said second mentioned power means for controlling the operation of the latter, said automatic means including a worm gear operatively connected to said differential gearing and adapted for axial movement in either direction from a neutral position, adjustable manual mechanism for controlling the axial movement of said worm gear, movable to three positions of adjustment, said mechanism when actuated to one position of adjustment permits movement of said worm gear in either direction from a neutral position, when said mechanism is moved to a second position of adjustment said worm gear is adapted for axial movement in one direction only from a neutral position, and when said mechanism is actuated to a third position of adjustment said worm gear is locked against axial movement in said neutral position.

6. In a device of the class described, the combination of a winch, including a cable winding drum, power means for actuating said drum to wind in or pay out cable, differential gearing disposed between said winding drum and power means, including a worm wheel, an hydraulic transmission for actuating said winding drum independently of said power means, a drive shaft for said hydraulic transmission, a worm gear mounted for axial movement keyed to said drive shaft and meshing with said worm wheel, whereby rotation of said shaft causes rotation of said worm gear and worm wheel, mechanism operatively connecting said worm gear to said transmission whereby axial movement of said gear controls the operation of said transmission, means for controlling the axial movement of said worm gear comprising a latch member, a rod secured to said worm gear having a collar thereon adapted to engage said latch member, said latch member being adapted for three positions of adjustment, when moved to one position of adjustment said latch member is out of engagement with said collar thereby permitting said worm gear to move in either direction from a neutral position, when moved to a second position of adjustment said latch member permits movement of said worm gear in one direction only from a neutral position, and when moved to a third position of adjustment said latch member engages said collar to lock said worm gear in neutral position, resilient means for actuating said worm gear in one direction, and means operating on said worm wheel for actuating said worm gear axially in the reverse direc-

tion against the action of said resilient means when a predetermined load is imposed upon said cable.

7. In a device of the class described, the combination of a winch, including a cable winding drum, means for actuating said drum to wind in or pay out cable, a second actuating means adapted to operate said drum independently of said first mentioned actuating means, and automatically operable fluid pressure means for controlling the operation of said second actuating means.

8. In a device of the class described, the combination of a winch including a cable winding drum, means for actuating said drum to wind in or pay out cable, differential gearing between said drum and actuating means, a second actuating means operatively connected to said differential gearing and adapted to operate said drum independently of said first mentioned actuating means, and automatically operable fluid pressure means for controlling the operation of said second actuating means.

9. In a device of the class described, the combination of a winch, including a cable winding drum, means for actuating said drum to wind in or pay out cable, differential gearing disposed between said drum and actuating means, an hydraulic transmission operatively connected to said differential gearing and adapted to actuate said drum independently of said actuating means, and automatic means for controlling the operation of said hydraulic transmission.

10. In a device of the class described, the combination of a winch, including a cable winding drum, means for actuating said drum to wind in or pay out cable, differential gearing disposed between said drum and actuating means, an hydraulic transmission operatively connected to said differential gearing and adapted to actuate said drum independently of said actuating means, and automatically operable fluid pressure means for controlling the operation of said hydraulic transmission.

45 11. In a device of the class described, the combination of a winch including a cable winding drum, means for actuating said drum to wind in or pay out cable, differential gearing disposed between said winding drum and actuating means, an hydraulic transmission operatively connected to said differential gearing and adapted to operate said drum independently of said actuating means, automatic means disposed between said gearing and said hydraulic transmission for controlling the operation of the latter, said automatic means including an axially movable member, a valve operatively connected to said member, fluid pressure means operatively connected to said transmission for conditioning the same for operation upon adjustment of said valve, and additional fluid pressure means controlled by said valve for actuating said transmission to neutral when said axially movable member assumes a neutral position.

65 12. In a device of the class described, the combination of a winch including a cable winding drum, power means for actuating said drum to wind in or pay out cable, differential gearing disposed between said winding drum and power means, a second power means operatively connected to said differential gearing and adapted to operate said drum independently of said first mentioned power means, automatic means disposed between said gearing and said second mentioned power means for controlling the opera-

tion of the latter, said automatic means including a worm gear operatively connected to said differential gearing and adapted for axial movement in either direction from a neutral position, fluid pressure means operatively connected to said second mentioned power means, a valve controlling the operation of said fluid pressure means, and means operatively connecting said valve to said worm gear.

13. In a device of the class described, the combination of a winch including a cable winding drum, power means for actuating said drum to wind in or pay out cable, differential gearing disposed between said winding drum and power means, a second power means operatively connected to said differential gearing and adapted to operate said winch independently of said first mentioned power means, automatic means disposed between said gearing and said second mentioned power means for controlling the operation of the latter, said automatic means including a worm gear operatively connected to said differential gearing and adapted for axial movement in either direction from a neutral position, fluid pressure means operatively connected to said second mentioned power means, a valve controlling the operation of said fluid pressure means, means operatively connecting said valve to said worm gear, and means for controlling the axial movement of said worm gear.

14. In a device of the class described, the combination of a winch including a cable winding drum, power means for actuating said drum to wind in or pay out cable, differential gearing disposed beneath said winding drum and power means, a second power means operatively connected to said differential gearing and adapted to operate said winch independently of said first mentioned power means, automatic means disposed between said gearing and said second mentioned power means for controlling the operation of the latter, said automatic means including a worm gear operatively connected to said differential gearing and adapted for axial movement in either direction from a neutral position, fluid pressure means operatively connected to said second mentioned power means, a valve controlling the operation of said fluid pressure means, means operatively connecting said valve to said worm gear, and adjustable means for controlling the axial movement of said worm gear, said last mentioned means when moved to one position permits axial movement of said worm gear in either direction from a neutral position, when moved to a second position of adjustment said means permits movement of said worm gear in one direction only from said neutral position, and when moved to a third position of adjustment said means locks said worm gear in neutral position.

15. In a device of the class described, the combination of a winch including a cable winding drum, means for actuating said drum to wind in or pay out cable, differential gearing disposed between said winding drum and actuating means, an hydraulic transmission operatively connected to said differential gearing and adapted to operate said drum independently of said actuating means, automatic means disposed between said gearing and said hydraulic transmission for controlling the operation of the latter, said automatic means including an axially movable member, a control valve operatively connected to said member, fluid pressure means operatively connected to said transmission for conditioning

the same for operation upon adjustment of said valve, additional fluid pressure means controlled by said valve for actuating said transmission to neutral, when said axially movable member assumes a neutral position, and a pump operatively connected to said control valve.

16. In a device of the class described, the combination of a winch including a cable winding drum, power means for actuating said drum to wind in or pay out cable, differential gearing disposed between said winding drum and power means, a second power means operatively connected to said differential gearing and adapted to operate said winch independently of said first mentioned power means, automatic means disposed between said gearing and said second mentioned power means for controlling the operation of the latter, said automatic means including a worm gear operatively connected to said differential gearing and adapted for axial movement in either direction from a neutral position, fluid pressure means operatively connected to said second mentioned power means, a valve controlling the operation of said fluid pressure means, means operatively connecting said valve to said worm gear, and a pump operatively connected to said valve.

17. In a device of the class described, the combination of a winch including a cable winding drum, power means for actuating said drum to wind in or pay out cable, differential gearing disposed between said winding drum and power means, a second power means operatively connected to said differential gearing and adapted to operate said winch independently of said first mentioned power means, automatic means disposed between said gearing and said second mentioned power means for controlling the operation of the latter, said automatic means including a worm gear operatively connected to said differential gearing and adapted for axial movement in either direction from a neutral position, fluid pressure means operatively connected to said second mentioned power means, a valve controlling the operation of said fluid pressure means, means operatively connecting said valve to said worm gear, a pump operatively connected to said valve, and a relief valve in the circuit between said valve and pump.

18. In a device of the class described, the combination of a winch including a cable winding drum, means for actuating said drum to wind in or pay out cable, differential gearing disposed between said winding drum and actuating means, an hydraulic transmission operatively connected to said differential gearing and adapted to operate said drum independently of said actuating means, automatic means disposed between said gearing and said hydraulic transmission for controlling the operation of the latter, said automatic means including an axially movable member, a control valve operatively connected to said member, fluid pressure means operatively connected to said transmission for conditioning the same for operation upon adjustment of said valve, additional fluid pressure means controlled by said valve for actuating said transmission to neutral, when said axially movable member assumes a neutral position, a pump operatively connected to said control valve, a relief valve in the circuit between said pump and control valve for bypassing fluid when the pressure therein exceeds a predetermined value, and an additional relief valve operatively connected to said control valve.

19. In a device of the class described, the combination with a winch including a cable winding drum, of power means for actuating said drum to wind in or pay out cable, gearing disposed between said winding drum and said power means, an hydraulic transmission for operating said winding drum independently of said power means, a member adapted for axial movement operatively connecting said hydraulic transmission to said gearing, stroke adjusting means connecting the pump end of said transmission with said member, resilient means for shifting said member in one direction to cause operation of said hydraulic transmission in one direction, and said gearing engaging said member and being adapted to shift the latter in the reverse direction to effect a reverse operation of said hydraulic transmission.

20. In a device of the class described, the combination with a winch including a cable winding drum, of power means for actuating said drum to wind in or pay out cable, gearing disposed between said winding drum and said power means, an hydraulic transmission for operating said winding drum independently of said power means, a member adapted for axial movement operatively connecting said hydraulic transmission to said gearing, stroke adjusting means connecting the pump end of said transmission with said member, resilient means for shifting said member in one direction to cause operation of said hydraulic transmission in one direction, said gearing engaging said member and being adapted to shift the latter in the reverse direction to effect a reverse operation of said hydraulic transmission, and means controlling the operation of said member.

21. In a device of the class described, the combination with a winch including a cable winding drum, of power means for actuating said drum to wind in or pay out cable, gearing disposed between said winding drum and said power means, an hydraulic transmission for operating said winding drum independently of said power means, a driving member adapted for rotary and axial movement operatively connecting said hydraulic transmission to said gearing, stroke adjusting means operatively connecting the pump end of said hydraulic transmission to said member, resilient means for shifting said member in one direction to effect operation of said transmission in one direction, said gearing engaging said member and being adapted to shift the latter in the reverse direction to effect a reverse operation of said transmission, and means for controlling the axial movement of said member.

22. In a device of the class described, the combination with a winch including a cable winding drum, of an hydraulic transmission for actuating said drum to wind in or pay out cable, gearing disposed between said winding drum and hydraulic transmission, means for controlling the operation of said transmission, a second hydraulic transmission for operating said winding drum, a member adapted for rotary and axial movements operatively connecting said second transmission to said gearing, stroke adjusting means for the pump end of said second hydraulic transmission operatively connected to said member, resilient means for actuating said member in one direction to effect operation of said second transmission in one direction, means operated by said gearing for actuating said member in the reverse direction to effect a reverse operation of said second hydraulic transmission,

and means for controlling the axial movement of said member.

23. In a device of the class described, the combination with a winch including a cable winding drum, of actuating means for said drum, gearing operatively connecting said drum and actuating means, additional means operatively connected to said gearing and adapted to operate said winding drum independently of said actu-

ating means, adjustable means for controlling the speed and direction of operation of said additional means, a shiftable member operatively connected to said gearing, and means connecting said shiftable member to said adjustable means, whereby any movement of said shiftable member is imparted to said adjustable means.

ROBERT C. LAMOND.
